UNITED STATES PATENT OFFICE.

EZRA T. GILLILAND, OF INDIANAPOLIS, INDIANA.

ARMATURE FOR MAGNETO-ELECTRIC MACHINES.

SPECIFICATION forming part of Letters Patent No. 270,945, dated January 23, 1883.

Application filed October 10, 1882. (No model.)

To all whom it may concern:

Be it known that I, EZRA T. GILLILAND, of the city of Indianapolis, county of Marion, and State of Indiana, have invented certain new and useful Improvements in Armatures for Magneto-Electric Machines, of which the following is a specification.

Heretofore there have been developed after a certain period of use in armatures of this character certain imperfections, which resulted principally from the unprotected condition of the helix.

In order to obtain the best results it is necessary, as is well known, to maintain the perfect insulation of the several convolutions of the wire composing the helix from each other, as any metallic contact between any of said convolutions will reduce the operative size of the helix, and to that extent impair the strength of the generator.

The helix, when constructed in the ordinary manner, being unprotected, except by the usual fibrous wrapping upon the wire, of which it is composed, is liable to be impregnated with grease from the journal-bearings of the armature, which grease, being filled with fine metallic particles worn from said bearings, soon establishes electrical connection between some of the convolutions of wire, and the effect is the same as if the helix were reduced in size, all the convolutions being "cut out" or "short-circuited," between which such electrical connection is established. In other cases (the wire composing the helix not usually being wound tightly enough to prevent it) there is a certain vibration of the convolutions of wire as the armature revolves, which causes the same to rub against each other, abrading the covering of said wire and allowing some of the convolutions to come in contact with each other, the effect being, as before, to short-circuit a portion of the helix.

My said invention therefore consists principally in so jacketing the helix of the rotary armature of a magneto-electric generator after it is wound upon its core as to prevent extraneous substances from getting among the convolutions thereof, to prevent the chafing of the covering of the wire composing it, and generally to obviate all those imperfections which

have heretofore resulted from its unprotected state.

It further consists of some details of construction and arrangement by which the armature is improved and its cost reduced. 55

Referring to the accompanying drawings, which are made a part hereof, and on which similar letters of reference indicate similar parts, Figure 1 is a vertical section on the dotted line *z z*, Fig. 2, through a call-signal apparatus for telephonic purposes embodying my said invention; Fig. 2, a vertical section thereof transversely of Fig. 1 on the dotted line *y y*, Fig. 1; Fig. 3, a horizontal section of the same on the dotted line *x x*, Fig. 2; and Fig. 65 4, a perspective view of the armature separately.

In said drawings, the portions marked A represent the permanent or horseshoe magnets of a magneto-electric generator; B, the pole-pieces thereof; C' C², &c., the various portions of the rotary armature; D, the cylinder-heads, and E contact-springs whereby the electrical circuit is established through the armature. 7c

The magnets A, pole-pieces B, cylinder-heads D, and contact-springs E may be constructed in any ordinary or suitable form, and need no special description. 75

The armature is constructed in the following manner: Upon the core C' the helix C² is 80 wound in the usual manner, except that the core does not extend into a shaft for the armature, and therefore the space ordinarily occupied by the shaft portions can be filled with additional wire and the strength of the apparatus in proportion to its size thus increased. After the helix is properly wound, paraffine or some similar fusible insulating material is introduced into the interstices therein, a wrapping, C⁴, of asbestos paper or some similar material capable of resisting the action of heat, is placed thereon, the whole is placed in a mold, and the intervening space is filled with molten white or other suitable metal, which, when cooled, entirely envelops the helix, (except the end by which the electrical connection is formed,) forming a jacket, C³, which completely protects it from all extraneous substances and holds it so firmly that any chafing or rubbing of the wires together is impossible. 95 100

The paraffine which is introduced into the helix makes it mechanically practically solid, and the asbestos paper C⁴ not only resists the action of heat during the casting of the jacket thereon, but serves as a means for the more perfect insulation of said helix.

The mold is so formed that the metal extends out at each end and forms journals for the armature. In each end of the mold, before the casting takes place, is placed a small hard-metal (preferably steel) ring or collar, c³, into which the metal runs, and thus, when the device is finished, the journals are covered with a much more durable metal than that of which they are principally composed, and are rendered as desirable in this respect as if the harder metal were used throughout, and at a small portion of the expense.

One journal is bored or cast hollow, as usual, and insulating material inserted, through which is passed a pin, c⁶, to lead off the electric current from the generator. By reason of the other unusual features of this armature, however, the construction is somewhat different. An open space extends down through the armature at the end where the hollow journal is attached, which is also lined with insulating material. A bar, c⁵, is placed in this space and rests against the pin c⁶. The end c² of the wire composing the helix is attached to this bar, and thus completes the electrical connection.

In the drawings the distinctively insulating material spoken of in this specification is dis-

tinguished from the metal or other parts by 35 being shown in solid black.

It will be understood that modifications in the construction or form of this armature may be made without departing from my invention, so long as the helix is jacketed, as described, 40 to protect the same.

Having thus fully described my said invention, what I claim as new, and desire to secure by Letters Patent, is—

1. A rotary armature for magneto-electric 45 generators, consisting of the usual core and helix and a metallic jacket cast upon and surrounding said helix, substantially as set forth.

2. An armature consisting essentially of the core C', the helix C², and the jacket C³, sub- 50 stantially as set forth.

3. An armature consisting essentially of the core C', the helix C², and the jacket C³, said jacket being continued to form the journals to the armature, substantially as set forth. 55

4. The combination of the core, the helix, the journals, the insulating material, the cross-bar c⁵, and the pin c⁶, said several parts being arranged and operating substantially as shown and specified. 60

In witness whereof I have hereunto set my hand and seal, at Indianapolis, Indiana, this 6th day of October, A. D. 1882.

EZRA T. GILLILAND. [L. S.]

In presence of—

C. BRADFORD,
E. W. BRADFORD.
